UNITED STATES PATENT OFFICE.

HARRY D. SEBRING, OF NEW YORK, N. Y.

DESIGN FOR A MEDICINAL CONTAINER.

58,948.

Specification for Design.

Patented Sept. 6, 1921.

Application filed January 17, 1921. Serial No. 438,034. Term of patent 3½ years.

To all whom it may concern:

Be it known that I, HARRY D. SEBRING, a citizen of the United States, residing at the borough and county of the Bronx, city and State of New York, have invented a new, original, and ornamental Design for Medicinal Containers, of which the following is a specification, reference being had to the accompanying drawing, forming part hereof.

I claim:

The ornamental design for a medicinal container, as shown.

HARRY D. SEBRING.

Witness:

GEO. DROMESHAUSER.
